CLARK ORR, OF FORT WAYNE, INDIANA, ASSIGNOR TO GENERAL ELECTRIC COMPANY,
A CORPORATION OF NEW YORK.

ROTARY REFRIGERATING-MACHINE.

1,273,653.

Specification of Letters Patent. Patented July 23, 1918.

Application filed September 15, 1916. Serial No. 120,256.

To all whom it may concern:

Be it known that I, CLARK ORR, a citizen of the United States, residing at Fort Wayne, in the county of Allen, State of Indiana, have invented certain new and useful Improvements in Rotary Refrigerating-Machines, of which the following is a specification.

My present invention relates to rotary refrigerating machines of the type comprising a closed evaporator and a closed condenser connected by a hollow shaft, the condenser having a compressor member freely mounted within the same. The condenser in such a refrigerating machine contains a refrigerating liquid, such as sulfur-dioxide, which is liquefied by compression and which subsequently vaporizes in the evaporator to which it is conveyed by a pipe or the like arranged within the hollow shaft. The evaporation of the refrigerating liquid produces a fall of temperature in the evaporator and may affect the refrigeration of a medium surrounding the same by absorbing heat therefrom. In such machines it is usual to remove the latent and mechanically generated heat from the compressed vapor in the condenser by a medium, such as water, circulated in contact with the wall of the condenser of the refrigerating machine.

In the operation of such machines it often happens that the medium which is to be cooled by the evaporators may be at a comparatively high temperature of say 55 to 65 degrees Fahrenheit. This is particularly true when such machines are used for cooling drinking water. Such a high temperature of the medium to be cooled raises the temperature of the vaporized refrigerating liquid in the evaporators and consequently the pressure thereof. Since the vapor is returned to the condensers of the machines to be again compressed, the pressure in the condensers also rises. If the medium used for cooling the condensers is at a high temperature the pressure in the condensers is similarly raised. As the pressure in the condensers of such machines increases, the compressor members tend to tilt in the direction of the rotation of the condensers and when this pressure rises to an abnormal value the compressor members will turn completely over within the condensers. The tilting of

the compressor members allows an excess of lubricating oil to enter the compressor cylinders and the downward movement of the compressor members in turning over causes a much more rapid movement of the pistons than in the normal operation of the machines, building up an enormous hydrostatic pressure in the cylinders, which has been known in some cases to blow out the cylinder heads of the compressors and in other cases to break the piston rods.

My invention has for one of its objects to provide means for effectively preventing the pressure of the vapor in the condenser from rising to an abnormal value and thus preventing the compressor member from turning over within the condenser. To this end I starve the evaporator by reducing the flow of refrigerating liquid thereto.

It is usual in such refrigerating machines as above described to provide within the evaporator a separator which is fastened to the tube which conveys the refrigerating liquid to the evaporator. This separator is provided with a passage above the hollow shaft through which the vapor of the refrigerating liquid may enter the hollow shaft and through which oil from the separator overflows. Since the above mentioned tube is fastened to the compressor member, it tilts when the compressor member tilts and raises the overflow point to such a height that the end of the hollow shaft may be completely submerged. This results in the cylinders drawing oil instead of vapor from the evaporator, causing hydrostatic pressure in the cylinders, which may also cause the cylinder heads to blow out or the piston rods to break.

Another object of my invention is to prevent an excess of oil from being drawn into the cylinders under these conditions, and to this end I provide the oil separator with an overflow spout, out of which oil will not flow when the separator is in its normal position, but out of which oil flows when the separator is tilted.

For a better understanding of my invention reference may be had to the following description taken in connection with the accompanying drawings, in which Figure 1 is a sectional view of a refrigerating machine embodying my invention; Fig. 2 is a

sectional view taken on the line 2--2 of Fig. 1 and looking in the direction of the arrows, and Fig. 3 is a sectional view taken on the line 3--3 of Fig. 1 looking in the direction of the arrows.

Referring to the drawings, 4 is a hollow shaft which carries and encloses a closed condenser 5 and a closed evaporator 6 and puts these two members in communication 10 for circulating the vapor and liquids. A compressor member 7 is freely mounted on the shaft within the condenser and is weighted by a weight 8 which prevents it from turning with the shaft 4 under normal 15 conditions. The compressor member has a reservoir 9 for containing the refrigerating liquid which is conveyed to the evaporator by suitable means such as a pipe 10 arranged within the hollow shaft 4. The reservoir 9 is provided with suitable means such as a valve 11 which operates upon the occurrence 20 of a high pressure in the condenser 5 to reduce the flow of the refrigerating liquid to the evaporator 6. This will be hereinafter 25 more fully described.

Fastened to the tube 10 within the evaporator 6 is an oil separator 12 which has a passage 13 located above the hollow shaft through which vapor from the evaporator 30 may enter the hollow shaft 4, and through which oil from the separator overflows. The oil separator 12 is provided with an overflow spout 14 mounted in the side thereof below the hollow shaft and arranged 35 so that in the normal position of the separator lubricant will not flow out of the end of this spout but if the separator is tilted from its normal position, lubricant will flow out of the spout into the evaporator.

40 The interior structure of this rotating refrigerating machine will now be described more fully in detail.

The compressor member 7 carries compressors and also the mechanism for distributing the lubricating oil and for circulating the same and separating it, and for circulating the liquids. The compressors, only one of which is shown in Fig. 1 of the drawings, are oscillating and double acting. 45 Each compressor is mounted in the compressor member by means of trunnions 15 and is provided with a piston 16. The piston rods 17 end in collars 18 which embrace an eccentric 19 mounted on the shaft 4 so 50 that the rotation of the shaft reciprocates the pistons. Each oscillating compressor cylinder carries on the inlet side a valve plate 20 furnished with two ports 21 which the oscillations of the cylinders alternately 55 put into communication with the inlet passages 22 in the compressor member. Each of the inlet passages open out opposite the end of the hollow shaft. The cylinders of the compressor are held tightly against the 60 valve plates 20 and the compressor member 65

by means of springs 23. The outlet ports and valves of the compressor are not shown in the drawing and may be of any usual construction.

A chamber 24 connects with the outlet 70 valves and has holes in the bottom thereof for allowing the refrigerating liquid which has been separated from the oil by gravity to escape into the condenser 5. The oil which remains in this chamber is supplied 75 to the working parts of the compressor and to the bearings 25. The liquid in the condenser 5 is collected by a scraper 26 and enters the settling chamber 27. The refrigerating liquid which is heavier than the oil, 80 which may have escaped with the refrigerating liquid from the chamber 24, settles in the sump 28 from which it is conveyed by a pipe 29 to the reservoir 9. The pipe 10 extends into the evaporator through the oil 85 separator 12 and serves to supply refrigerating liquid to the evaporator. It is fastened to the compressor member and therefore does not revolve with the hollow shaft 4, but extends therethrough. In the reservoir 9 is a 90 valve 30 with a float 31 for controlling the opening of the pipe 10 so as to allow refrigerating liquid to pass into the evaporator when enough has entered the reservoir to raise the float. The valve 11 in the side of 95 the reservoir 9 is pivotally mounted on a stud 32 and is held closed by means of a weight 33 so long as the compressor member remains in its normal or vertical position. The shaft 4 is provided with an equalizing 100 valve 34, the object of which is to instantly equalize the vapor pressures in the machine as soon as it stops, and consequently to very rapidly equalize the temperatures in the condenser and the evaporator by automatically 105 putting them into communication. This valve is closed by a weight 35 thrown out by centrifugal force and is opened by a spring 36. This weight 35 and the spring 36 are so proportioned that the valve 34 is closed when the machine arrives at about 110 60 per cent. of its speed, the valve remaining closed until the machine falls to about 40 per cent. of its speed. Without this equalizing valve the refrigerating machine 115 would require a very large motor to start it, much larger than is necessary to run it after it has started.

The oil separator 12 comprises a box containing three chambers 37, 38 and 39, chambers 37 and 39 being in effect a single chamber connected by a pipe 40. The oil separator has a central casting comprising a sleeve 41 fitting over the end of the hollow shaft 4 and being free thereon and a clamp 120 42 for rigidly fastening the oil separator to the pipe 10 so that the oil separator will remain in an upright position under normal 125 conditions of operation of the refrigerating machine. This casting is provided with a 130

hole or passage 13 located above the sleeve 41 through which the vaporized refrigerating liquid passes to enter the hollow shaft 4. Scrapers 43 serve to automatically collect 5 and bring into the settling chambers of the separator the refrigerating liquid and oil, the oil and sulfur dioxide separating in the chambers 37 and 39 by gravity; the sulfur dioxide settling at the bottom and forcing 10 the oil ahead of it. The distributing pipe 44 extends upwardly from the lowermost part of the separating chamber 39 and passes through the side wall of this chamber. This pipe discharges refrigerating liquid against 15 the wall of the evaporator 6. The refrigerating liquid and oil collected in the chamber 38 flows out of the distributing pipe 45 and is also discharged against the wall of the evaporator. The overflow spout 14, as 20 already explained above, is also mounted in the side of the separator below the hollow shaft, connecting with the top of the settling chamber 39, and extends in a plane at right angles to the axis of the pipe 10 and hollow 25 shaft 4 and upwardly at an acute angle to the separator so that oil will not flow out of the end thereof when the separator is in its normal vertical position but will flow out of the end thereof when the separator 30 is tilted from its normal position.

The operation of the machine is as follows: The compressors draw from the evaporator 6 the vapor of the refrigerating liquid through the passage 13 in the central casting of the separator 12, through the hollow shaft 4 into pockets 46, through cored passages in the compressor member 7 (not shown), inlet passages 22, ports 21, and after compressing the vapor, force it out 35 through outlet valves (not shown), into the chamber 24 of the compressor member from which it enters the condenser 5. The refrigerating liquid is continuously collected by the scraper 26, which passes it into the 40 separating chamber 27, where it is separated by gravity from any oil which may also be collected by the scraper, the refrigerating liquid entering the reservoir 9 through the pipe 29. The refrigerating liquid enters the 45 evaporator from the reservoir 9 through the pipe 10 whenever the valve 30 is open. The evaporation of the refrigerating liquid in the evaporator cools the same and the vapor is then pumped back through the hollow 50 shaft 4 as explained above. When the machine is in operation the tendency is for the compressor member to rotate in the same direction as the condenser and refrigerator are rotating, which is clockwise facing the 55 condenser in the arrangement shown, but this is counteracted by the counterweight 8 which holds the carrier approximately in a vertical position. If, however, the pressure in the condenser becomes high, due to the 60 high temperature of the evaporator or con-

denser, the compressor member tilts from its normal vertical position. As the tube 10 is fastened to the compressor member and the oil separator in turn is fastened to the tube, the oil separator tends to tilt with the compressor member. The tilting of the compressor member allows lubricating oil to drain into the cylinders and puts the cylinders in a much poorer position for the discharge of the oil than 70 when in their normal position. If the pressure of the vapor in the condenser member is permitted to rise to an abnormal value the compressor member will turn over within the condenser 5, and will then impart 75 in its downward movement a much more rapid displacement of the pistons than is given by the normal rotation of the machine. Since the outlet ports of the cylinders are relatively small, the cylinders will not 80 empty themselves quickly enough to prevent the building up of enormous hydrostatic pressures due to the incompressibility of the oil and either a cylinder head or a piston rod breaks. In order to prevent the pressure 85 of the vapor in the condenser rising to such a high value as to cause the condenser to turn over, I have provided the valve 11, which, when the compressor member tilts due to an increase in the pressure 90 of the vapor, will be opened by means of the weight 33, permitting refrigerating liquid to flow out of the reservoir 9 into the condenser 5, the float 31 falling and closing the valve 30, thus stopping the flow 95 of the refrigerating liquid into the evaporator, starving the evaporator of the refrigerating liquid and consequently reducing the pressure of the vapor in the evaporator and in the condenser. The tilting of the 100 compressor member also tilts the oil separator as well, since the oil separator is fastened to the tube 10 and the tube 10 is rigidly fastened in the compressor member. This tilting of the oil separator causes the 105 position of the passage 13 out of which oil overflows from the settling chamber 39 in the normal position of the separator to change with relation to the center line of the hollow shaft, and except for the presence 110 of the overflow spout 14, this change of the relative position of the passage 13 would raise the overflow point of the oil to such a degree that the end of the hollow shaft may be almost completely submerged 115 with the result that the cylinders would be drawing oil instead of vapor from the evaporator. By providing the overflow spout 14 oil will flow out of the end thereof when the oil separator is tilted and prevent the 120 submerging of the end of the hollow shaft and consequently prevent an excess of oil from being drawn into the cylinders. Without this overflow spout large quantities of oil would be drawn into the cylinders when 125 130

the separator is tilted at an angle to the vertical which would cause hydrostatic pressure in the cylinders and probably break the cylinder heads or piston rods.

5 I desire to be understood that my invention is not limited to the particular arrangement shown and described, and I aim in the appended claims to cover all modifications which do not depart from the spirit 10 and scope of my invention.

What I claim as new and desire to secure by Letters Patent of the United States, is:

1. In a rotary refrigerating machine, a closed condenser, a closed evaporator, a hollow connecting shaft, a member freely mounted on the shaft in said condenser provided with a reservoir for refrigerating liquid, means for conveying refrigerating liquid to the evaporator, and means operative upon the occurrence of a high pressure in said condenser for stopping the flow of refrigerating liquid to said evaporator.

2. In a rotary refrigerating machine, a closed condenser, a closed evaporator, a hollow connecting shaft, a member freely mounted on the shaft in said condenser provided with a reservoir for refrigerating liquid, means for conveying refrigerating liquid to the evaporator, and a valve in the side of said reservoir for releasing refrigerating liquid therefrom upon the occurrence of a high pressure in said condenser.

3. In a rotary refrigerating machine, a closed condenser, a closed evaporator, a hollow connecting shaft, a member freely mounted on the shaft in said condenser provided with a reservoir for refrigerating liquid, means for conveying refrigerating liquid to the evaporator, and a valve in the side of said reservoir for releasing refrigerating liquid therefrom, said valve being opened by a tilting movement of said member about the axis of said hollow shaft.

4. In a rotary refrigerating machine, a closed condenser, a closed evaporator, a hollow connecting shaft, a member freely mounted on the shaft in said condenser provided with a reservoir for refrigerating liquid, means for conveying refrigerating liquid to the evaporator, and a valve in the side of said reservoir pivotally mounted on the side thereof and being provided with a weight for holding said valve closed when said member is in its normal position and for opening said valve when said member is tilted about the axis of said hollow shaft.

5. In a rotary refrigerating machine, a closed condenser, a closed evaporator, a hollow connecting shaft, a reservoir for the refrigerating liquid located within said condenser, a pipe communicating therewith for leading the refrigerating liquid to the evaporator and arranged within said hollow shaft, an oil separator hung within said evapora-

tor and fastened to said pipe, said separator having a passage through which vapor from the evaporator may enter said hollow shaft, said passage being located above said shaft, and an overflow spout mounted in the side of said separator below said hollow shaft and arranged so that oil will not flow out of the end thereof if the separator is in its normal position but will flow out of the end thereof if the separator is tilted from its normal position.

6. In a rotary refrigerating machine, a closed condenser, a closed evaporator, a hollow connecting shaft, a reservoir for the refrigerating liquid located within said condenser, a pipe communicating therewith for leading the refrigerating liquid to the evaporator and arranged within said hollow shaft, an oil separator hung within said evaporator and fastened to said pipe, said separator having a passage through which vapor from the evaporator may enter said hollow shaft, said passage being located above said shaft, and an overflow spout mounted in the side of said separator below said hollow shaft, said spout extending upwardly at an acute angle to said separator so that oil will not flow out of the end thereof if the separator is in its normal position but will flow out of the end thereof if the separator is tilted from its normal position.

7. In a rotary refrigerating machine, a closed condenser, a closed evaporator, a hollow connecting shaft, a reservoir for the refrigerating liquid located within said condenser, a pipe communicating therewith for leading the refrigerating liquid to the evaporator and arranged within said hollow shaft, an oil separator hung within said evaporator and fastened to said pipe, said separator having a passage through which vapor from the evaporator may enter said hollow shaft, said passage being located above said shaft, and an overflow spout mounted in the side of said separator below said hollow shaft, said spout extending in a plane at right angles to the axis of said pipe and hollow shaft and arranged so that oil will not flow out of the end thereof if the separator is in its normal position but will flow out of the end thereof if the separator is tilted from its normal position.

8. In a rotary refrigerating machine, a closed condenser, a closed evaporator, a hollow connecting shaft, a reservoir for the refrigerating liquid located within said condenser, a pipe communicating therewith for leading the refrigerating liquid to the evaporator and arranged within said hollow shaft, an oil separator hung within said evaporator and fastened to said pipe, said separator having a passage through which vapor from the evaporator may enter said hollow shaft, said passage being located

above said shaft, and an overflow spout mounted in the side of said separator below said hollow shaft, said spout extending upwardly at an acute angle to said separator 5 and in a plane at right angles to the axis of said pipe and hollow shaft so that oil will not flow out of the end thereof if the

separator is in its normal position but will flow out of the end thereof if the separator is tilted from its normal position. 10

In witness whereof I have hereunto set my hand this 11th day of September, 1916.

CLARK ORR.
